Primary Examiner — Catherine Tuttle(74) *Attorney, Agent, or Firm* — The Law Office of Austin Bonderer, PC; Austin Bonderer(57) **CLAIM**

The ornamental design for a ball tee, as shown and described.

DESCRIPTION

FIG. 1 is an upper perspective view of the ball tee showing my new design;

FIG. 2 is a lower perspective view thereof;

FIG. 3 is a side elevational view thereof;

FIG. 4 is another side elevational view thereof, rotated 90° from FIG. 3;

FIG. 5 is a top plan view thereof;

FIG. 6 is a bottom plan view thereof;

FIG. 7 is an upper perspective view showing a second embodiment of my new design;

FIG. 8 is a lower perspective view thereof;

FIG. 9 is a side elevational view thereof;

FIG. 10 is another side elevational view thereof, rotated 90° from FIG. 3;

FIG. 11 is a top plan view thereof; and,

FIG. 12 is a bottom plan view thereof.

1 Claim, 4 Drawing Sheets(56)
